UNITED STATES PATENT OFFICE

2,462,409

SHIRT AND TROUSER HOLDER

Claude C. Levin, Jacksonville, Fla.

Application January 14, 1944. Serial No. 518,266

1 Claim. (Cl. 24—83)

1

This invention relates to a shirt and trouser holder, and has for one of its objects the production of a simple and efficient means for supporting trousers in place without the use of suspenders which extend over the shoulders of the wearer.

A further object of this invention is the production of a simple and efficient trouser support consisting of a plurality of sets of interfitting members, one member of each set being carried by the trousers, and the other member being carried by the shirt, said interfitting members being constructed so as to be readily attached and also easily detached.

Another object of this invention is the production of a simple and efficient shirt-engaging member having a spring clamp which may be conveniently operated to quickly attach the member to a shirt and to readily release the member therefrom without injury to the shirt.

Other objects and advantages of this invention will appear throughout the following specification and claim.

In the drawings:

Figure 1 is a front elevational view of the male member of one pair of holders;

Figure 2 is a rear elevational view thereof;

Figure 3 is an edge elevational view, certain parts being shown in section, and illustrating the manner of attaching the male member and securing the same to the top edge of the trousers;

Figure 4 is a top plan view of the male member;

Figure 5 is a front elevational view of the female member of one pair of holders above referred to;

Figure 6 is a rear elevational view thereof;

Figure 7 is a side elevational view of the structure shown in Figure 6;

Figure 8 is a top plan view of the members assembled;

Figure 9 is an enlarged fragmentary transverse sectional view taken on line 9—9 of Figure 6, looking in the direction of the arrow.

By referring to the drawings, it will be seen that 10 designates the male member of one set of trouser-holders. This member 10 comprises a tapering body having inwardly rolled edges 11 and 11^a. The male member 10 is provided with a right-angular flange 12 at the top thereof. A depending tongue 13 extends downwardly from the flange 12 in spaced relation to the body of the member 10, as shown in Figure 3. An outer clamping tongue 14 extends downwardly from the outer end of the flange 12 in spaced relation to the tongue 13 to provide a pocket therebetween to receive the top edge of a pair of trousers 9. A clamping set screw 14^a is carried by the tongue

2

14 for gripping the trousers and clamping the male member in place, as shown in Figure 3. The arrangement of the tongue 13 in spaced relation to the body of the male member 10 will hold this member away from the inner face of the trousers for a sufficient distance to prevent the crowding of the female member when assembled with the male member.

In Figures 5, 6 and 7, inclusive, I have shown 10 the type of female member preferably used with the male member above described. This female member 15 comprises a tapering body having inwardly rolled edges 16 and 16^a. A longitudinally extending elongated spring clamp 17 of the conventional type is hingedly secured at one side edge of the female member 15, as shown. This spring clamp 17 is preferably hinged upon a suitable pintle 18, the ends of which are carried in the journals 19 and 19^a. It should be understood, however, that any suitable type of spring clamp 17 may be employed without departing from the spirit of the invention, and that the spring clamp 17 may be hinged to the female member in any suitable manner to freely swing so that the clamp 17 may grip the side of a shirt at the side seam thereof to attach the female member to the shirt adjacent the top edge of an adjoining pair of trousers carrying the companion male member.

The male member 10 is attached to the trousers 30 at the top edge thereof, so as to fit upon the inner face of the trousers adjacent the top edge of the trousers. The female member 15 is secured to the shirt by attaching the clamp 17 at selected points adjacent the side seams of the shirt, as explained 35 in the following, the clamp 17 extending in a substantially vertical direction. The small end 7 of the male member 10 is then dropped into the upper end 8 of the female member 15 and the weight of the trousers will cause the male member 10 to wedge downwardly into the member 15 thereby holding the members in assembled relation, as shown in Figure 8. The female member 15 of two of the holders, by being clamped to the shirt, preferably adjacent the hip of the wearer at the side seams of the shirt, will suspend the member 10 in clamped engagement with the member 15. I preferably employ one set of holders as described above upon each side of the trousers adjacent the hips of the wearer, and one set in front so that the clamp may engage the shirt at the point where it is buttoned together. The male and female members above described comprise interfitting wedge-like members wherein the female member, which is releasably secured to the shirt by the spring clamp, receives the wedge-

like male member which in turn is carried by the trousers. There is, therefore, provided an efficient suspension support to prevent the sagging of the trousers at a point adjacent the hips of the wearer. The members 13 and 15 may be preferably made of metal although other material may be employed without departing from the spirit of the invention. When it is desired to separate the members, the member 16 may be lifted upwardly from the member 15, and if desired, the rolled edges 11 and 11^a may be pinched toward each other to release the edges 11 and 11^a from the rolled edges 16 and 16^a.

It should be noted that the spring clamp 11 which is of a conventional type extends longitudinally or vertically of the female member 15 for a major portion of its length, and is hingedly connected near one of the side flanges. A clamp of this type is provided as shown, with a pair of elongated flat gripping jaws, a clamp of this type being particularly adapted for use in connection with the present structure, and forming an important element thereof due to the fact that it is necessary and of great advantage to provide a broad gripping area for the clamp so that the fabric of the shirt may be efficiently gripped to support the member 15 in engagement with the shirt, and thereby avoid the danger of tearing the shirt where the clamp grips the fabric of the shirt.

Having described the invention, what is claimed as new is:

A device of the class described comprising an elongated clamp having engagement with a shirt, a first connecting member and a pivotal connection between said clamp and said first member, a second connecting member having means for attachment to a pair of trousers, a separable interlocking connection between said first and second members; said pivotal connection between the clamp and the first member providing flexibility in the connection between a shirt and trousers.
